UNITED STATES PATENT OFFICE.

WILLIAM L. GARRELS, OF ST. LOUIS, AND CLINTON KIMBALL, OF KIRKWOOD, MISSOURI.

LUBRICATOR.

SPECIFICATION forming part of Letters Patent No. 667,148, dated January 29, 1901.

Application filed July 3, 1900. Serial No. 22,400. (No model.)

To all whom it may concern:

Be it known that we, WILLIAM L. GARRELS, a resident of the city of St. Louis, and CLINTON KIMBALL, a resident of the city of Kirkwood, St. Louis county, State of Missouri, citizens of the United States, have invented certain new and useful Improvements in Lubricators, of which the following is a specification.

Our invention relates to lubricators for steam-engine cylinders, and has for its principal object to provide for the lubrication of the cylinders and valves of steam-engines when it is desirable to place the parts of the lubricator substantially below the connection between the lubricator and the steam-pipe or throttle-valve.

Other objects are convenience of manipulation, compactness of construction, and the improvement of the construction in general.

It also consists in the arrangements and combinations of parts hereinafter described and claimed.

In the accompanying drawings, which form part of this specification, and wherein like symbols refer to like parts wherever they occur, Figure 1 is a vertical sectional view of our device. Fig. 2 is a vertical sectional view of a modification wherein the outer member of the swivel is formed on the reversible portion of the device. Fig. 3 is a vertical view, partly sectional, showing the reservoir made of glass and a passage-way through the piston. Fig. 4 is a cross-section of the device illustrated in Fig. 3, and Fig. 5 is a vertical section of a modified form of our device.

The oil-reservoir of our device consists of a hollow cylinder 1, containing a piston or plunger 2. The end of the cylinder 1 which is the lower end when the device is in its working position is closed by a filling-plug 3. A passage-way 4 connects the said lower end of the cylinder 1 through a valve 5 for regulating the feed of the oil to a passage-way 6. In order to indicate the condition of the feed, one or more bull's-eyes 7 or a glass tube are inserted in said passage-way 6. A passage-way 8, which opens into the end of the cylinder opposite the filling-plug, and the passage-way 6, both extend upwardly when the device is in its working position into a substantially horizontally-arranged cylindrical or

conical cock or swivel-stem 9. The passage-way 6 and the passage-way 8 both open into a passage-way 10, formed in the casing 11 of the swivel-stem. Said passage-way 10 communicates with the steam-pipe 12 or with the throttle-valve of the engine the valves and cylinders of which are to be lubricated. In order to insure easy working of the swivel 9 and prevention of leakage, it is preferable, especially for a high steam-pressure, to provide each end of the swivel with packing 13. Said packing at each end is made independently adjustable with respect to the packing at the other end by means of the nuts 14, which screw onto the swivel-stem 9. When the swivel is turned half a turn, the passage-way 8 registers with the drain 15, while the passage-way 6 is closed. It is preferable to provide said drain 15 with a valve 16 for controlling the drain and also, especially when high steam-pressure is used, to prevent leakage from the passage-way 10 into the surrounding atmosphere.

The operation of filling our device with oil and of feeding the oil for use is as follows: When the device is in its working position, condensed steam fills the part of the cylinder 1 above the piston 2 and also fills the passage-way 8, the passage-way 6, and the passage-way 10 up to the place of connection with the steam-pipe 12 or with the throttle-valve. To fill the lubricator, it is turned on the swivel-stem into its inverted position. In this position communication with the steam-pipe is cut off and the passage-way 6 is closed. The water in said passage-way 6 consequently remains in it. The filler-plug 3 is then removed. The water in the cylinder 1 is now drained off by opening the valve 16. This causes the piston 2 to sink on account of its weight to what in the working position of the device is the top of the cylinder 1. The oil-reservoir 1 is now filled with oil and the filler-plug 3 is replaced. When the lubricator is turned into its lower position, it is ready to feed, the adjustment of the valve 5 not having been changed and the water in the passage-ways 6 and 10 not having been drained during the operation of filling. The pressure required to force the lubricant through the valve 5, which is preferably a needle-valve,

is obtained from the weight of the piston 2 itself, the means for exerting pressure on the oil being thus entirely inside of the cylinder. The drops of oil after passing the valve 5 float up through the passage-ways 6 and 10 and then flow into the steam-pipe or throttle-valve. Any leakage of oil past the piston 2 would have the effect merely of feeding to the engine a slightly-additional amount of lubricant, which would not be visible at the said sight-glass. As the passage-ways 6 and 8 lead to the same source of steam-pressure and the piston is consequently subjected to the same steam-pressure on both sides, it is obvious that the pressure on both sides due to the steam is balanced. Obviously, therefore, any other arrangement of passage-ways which will result in balancing the steam-pressure on the two sides of the piston is the equivalent of the two passage-ways 6 and 8 and may be substituted therefor for equalizing the pressure in the ends of the cylinder—as, for instance, an opening directly through or past the piston, such as a groove cut into the piston or cylinder wall. Fig. 3 shows such a modification. In this modification the passage-ways 4 and 6 are located in the piston 2 itself. So, also, the valve 5, if used, should be mounted in said piston; but obviously the valve may be omitted entirely. In this modification the sight-glass 17 forms the walls of the cylinder 1, thus showing not only the condition of the feed, but also the quantity of oil in the reservoir. A sight-glass could obviously be placed in either the passage-way 8 or the passage-way 10.

Our device is especially adapted for use in connection with steam-automobiles, as no part of it need be above the place of connection with the steam-pipe or throttle-valve. When the vehicle is stopped, the device may be turned into its inverted position and the feed of the oil thereby stopped. If the driver should forget to turn it back upon again starting, it will turn back automatically on account of its weight and of the vibration of the vehicle.

Divers modifications may be made in the construction above described without departing from our invention. For instance, the passage-ways 6 and 8 may enter the casing through the end of the swivel-stem. The body portion or stem of the lubricator may be made to form the female part of the swivel, as shown in Fig. 2. So, too, the passage-ways 6 and 8 may be made to both register with a drain 15, as indicated by the dotted line in Fig. 2. In case the device to be lubricated is exposed to atmospheric pressure the end of the cylinder may be left open to the atmosphere, so as to equalize the pressure on the piston therein in opposite directions. Ordinary journals, axles, and slides are illustrations of such a case. It is usual to feed the oil or grease to such devices downwardly instead of upwardly, and our invention contemplates feeding the lubricant in either di-

rection. When it is desired to use a perforated piston or weight for lubricating such bearings, a groove 18 may be cut in its side 70 from the top nearly to the bottom of said piston and in position to register with a port or passage-way 19, connected to the bearing to be lubricated, as will be obvious from an inspection of Fig. 5 of the drawings. 75

Our invention admits of various other modifications, and we do not wish to limit ourselves to the above details of construction.

What we claim is—

1. A lubricator comprising a reversible 80 body having a chamber and passage-ways extending therefrom and a piston in said chamber, one of said passage-ways having an opening for communicating with the steam-pipe, substantially as described. 85

2. A lubricator comprising a reversible body having a chamber and passage-ways extending from the end portions thereof and communicating with the steam-pipe and a sight-feed in one of said passage-ways, and a piston in said chamber, substantially as described. 90

3. A lubricator comprising a body having a chamber and passage-ways extending from the upper and lower portions thereof and a heavy piston in said chamber, whereby said piston, located entirely within said chamber, constitutes the means for exerting pressure, substantially as described. 95

4. A lubricator having a reversible body 100 portion having a swivel-stem and comprising a chamber, a pressure-transmitting device therein and passage-ways extending from the respective ends thereof through the swivel-stem, and a casing in which said stem swivels, said casing being provided with an opening constituting a connection between the passage-ways of said stem and the steam-pipe, substantially as described. 105

5. A lubricator having a reversible body 110 portion having a swivel-stem and comprising a chamber, a pressure-transmitting device therein and passage-ways extending from the respective ends thereof through said swivel-stem, and a casing in which said stem swivels, 115 said casing being provided with an opening constituting a connection between the passage-ways of said stem and the steam-pipe, and a drain-outlet arranged to register with a port in said stem which communicates with 120 the upper end of the chamber and arranged to close the other port, substantially as described. 125

6. A lubricator having a reversible body portion having a swivel-stem and comprising a chamber and a pressure-transmitting device 130 therein and passage-ways extending from the respective ends thereof through said swivel-stem to the steam-pipe and a casing in which said stem swivels, said casing being provided with openings adapted to connect with the steam-pipe and with the drain-outlet, and the passage-ways in said swivel-stem being so arranged that they register with the drain-out-

- let when the device is inverted, substantially as described.
7. A lubricator having a body portion swiveled on a stem and comprising a chamber, a piston therein, a casing for said stem having an opening communicating with the steam-pipe and an opening to a drain-pipe, said body having a passage-way leading from the upper end of the chamber through said stem and terminating in a port in the side of said stem in position to register with both of the openings in said casing in turn, and a valved passage-way leading from the feed end of the chamber through said stem in position to register with the steam-opening only of said casing, substantially as described.
8. A lubricator comprising a body having a chamber in its lower portion and an offset therefrom, passage-ways extending upwardly from said body and communicating with a steam-pipe or with a passage-way common to said first-mentioned passage-ways and adapted in turn to communicate with the steam-pipe, and a piston in said chamber, one of the upwardly-extending passage-ways being in the offset, substantially as described.
9. A lubricator comprising a body having a chamber in its lower portion and an offset therefrom and passage-ways extending upwardly from said body and communicating with a steam-pipe or with a passage-way common to said first-mentioned passage-ways, and adapted in turn to communicate with a steam-pipe and a piston in said chamber, one of the upwardly-extending passage-ways being in the offset and a valve for the passage-way therein arranged at the bottom of the offset portion, substantially as described.
10. A lubricator comprising a body having a swivel-stem and a chamber and passage-ways extending from the upper and lower ends of said chamber through said stem to the steam-pipe and a piston in said chamber, and a valve for the passage-way communicating with the lower end of said chamber, substantially as described.
11. A lubricator comprising a body having a swivel-stem and a chamber and passage-ways extending upwardly from the upper and lower ends of said chamber and communicating through said stem with the steam-pipe, and a piston in said chamber, said body having an opening communicating with the lower end of said chamber for filling the same and a plug for said opening, substantially as described.
12. A lubricator comprising a body having a chamber in its lower portion and an offset therefrom and passage-ways extending upwardly from said body and communicating with a steam-pipe or with a passage-way common to said first-mentioned passage-ways and adapted in turn to communicate with a steam-pipe, and a piston in said chamber, the lower of the upwardly-extending passage-ways being in the offset, a sight-glass in said first-mentioned passage-way and a valve in said pas-
- sage-way between said sight-glass and said chamber, substantially as described.
13. A lubricator comprising a body having a perforated swivel-stem, and a casing, said stem being longitudinally adjustable in said casing and provided with means for packing said stem in its adjusted position, substantially as described.
14. A lubricator comprising a body having a conical, perforated swivel-stem and a casing, said stem fitting in said casing and being threaded on each side thereof and provided with packing and nuts to pack it in its adjusted position, substantially as described.
15. A lubricator comprising a body having one member of a swivel, the second member of said swivel being arranged for connection to the device to be lubricated, the inner member of said swivel projecting through the outer member and having its projecting portions threaded at each side of the outer member and provided with nuts working thereon, substantially as described.
16. A lubricator comprising a body having one member of a swivel, the second member of said swivel being arranged for connection to the device to be lubricated, the inner member of said swivel projecting through the outer member and having its projecting portions threaded at each side of the outer member and provided with nuts working thereon, and packing around the inner member between said nuts and the outer member, substantially as described.
17. A lubricator comprising a body having a swivel-stem and a casing for said stem, said stem being threaded on opposite sides of said casing and having packing and nuts thereon whereby said stem may be adjusted longitudinally in said casing, said stem and casing having registering passage-ways for feeding oil, substantially as described.
18. A lubricator comprising a body, a chamber therein, a piston in said chamber, said body having one member of a swivel integral therewith, the second member of said swivel being adapted for connection to the device to be lubricated, and each of said members having passage-ways adapted to communicate with the oil-reservoir and with the device to be lubricated, respectively, substantially as described.
19. A lubricator comprising a body, a chamber therein and a piston wholly within said chamber, said body having a swivel-stem and having one or more passage-ways extending through said stem and communicating with said chamber on both sides of said piston, and a casing for said swivel-stem having one or more passage-ways communicating with the device to be lubricated and adapted to register with said passage-ways in the swivel-stem, substantially as described.
20. A lubricator comprising a body having a chamber, a piston wholly within said chamber, a passage-way from said chamber for the lubricant, and ports for balancing the pres-

sure on the two sides of said piston, substantially as described.

21. A lubricator comprising a body having a chamber, a piston of uniform diameter in said chamber, a passage-way communicating with the device to be lubricated; said passage-way communicating with said chamber on both sides of said piston, substantially as described.

15 22. A lubricator comprising a body having a chamber in its lower portion, a piston in said chamber, constituting a weight for exerting pressure on the lubricant, a passage-way extending upwardly therefrom and communicating with the device to be lubricated, and a passage-way in said piston, substantially as described.

23. A lubricator comprising a body having a chamber in its lower portion, a piston in said chamber, constituting a weight for exerting pressure on the lubricant, a passage-way extending upwardly therefrom and communicating with the device to be lubricated, a pas-

sage-way in said piston and a valve in said passage-way, substantially as described.

24. A lubricator comprising a body having a chamber in its lower portion, a piston in said chamber, constituting a weight for exerting pressure on the lubricant, a passage-way extending upwardly therefrom and communicating with the device to be lubricated, a sight-glass in either said chamber or said passage-way and a passage-way in said piston, substantially as described.

25. A lubricator comprising a reversible body having a chamber in its lower portion, a piston in said chamber, a passage-way extending upwardly therefrom and communicating with the device to be lubricated, and a passage-way in said piston, substantially as described.

W. L. GARRELS.
CLINTON KIMBALL.
